UNITED STATES PATENT OFFICE.

EDWARD FOWLER, OF CEDAR GROVE, GEORGIA, ASSIGNOR OF ONE-HALF
TO THOMAS B. SIMMONS AND JESSEY L. SIMMONS, OF SAME PLACE.

PLOW.

SPECIFICATION forming part of Letters Patent No. 653,668, dated July 17, 1900.

Application filed November 15, 1899. Serial No. 737,086. (No model.)

To all whom it may concern:

Be it known that I, EDWARD FOWLER, a citizen of the United States, and a resident of Cedar Grove, in the county of Walker and State of Georgia, have invented certain new and useful Improvements in Plows, of which the following is a specification.

This invention relates to plows generally, and more especially to the disk plow; and it consists of the parts and combination of parts hereinafter set forth.

In the drawings, Figure 1 is a perspective view of my improved plow. Fig. 2 is a similar view with parts broken away and the disk removed. Fig. 3 is a perspective view of the landside. Fig. 4 is a similar view of the point.

1 represents the beam, of I shape in cross-section and given a curvature desired by the manufacturer.

2 is a vertical standard integral with and depending from the beam 1, said standard being provided with a series of bolt holes or openings 3. The standard 2 must be straight from its juncture with the beam 1 to its lower end.

4 is a forwardly-extending lug integral with the bottom of the standard 2 and provided with suitable bolt openings or holes 5.

6 is the landside, provided with a series of bolt-openings 7 and 8, said landside being connected to the standard by means of bolts 9, which pass through the openings 5 in the standard and 7 in the landside.

10 is a brace the rear end of which is provided with a series of bolt-openings 11, the forward end of said brace being secured to the landside by means of a bolt 12, which passes through said brace and through one of the openings 8 in the landside, according to the adjustment of the same. The other end of the brace 10 is adjustably secured to the standard 2 by means of the bolt 13, which passes through one of the series of openings 3 in said standard.

45 14 is a lug extending from one side of the point of the landside, and 15 is an upwardly-extending flange on the outer edge of said lug. 16 is a bolt-opening in the landside. 17 is the plow-point, provided with an elongated slot 18, through which the bolt 19 passes

into the bolt-opening 16 on the landside to adjustably secure said point to the landside. This point 17 is secured as just described, and is prevented from turning crosswise of the draft by means of the flange 15. The 55 point may also be adjusted up and down by means of the elongated slot 18, and when one end of said point is worn it may be reversed by loosening the bolt 19 to present a new point to the ground.

60 20 represents handle-brackets secured to the standard 2 by means of a suitable bolt. 21 represents the usual shares connected to said brackets, and 22 represents braces extending from the upper end of said handles to 65 the plow-beam in the usual manner.

23 is a plate having a bolt-opening near each end, and 24 is a ball-bearing journal-box integral with said plate. This plate is adjustably secured in the desired position on 70 the standard 2 by means of the bolts 25.

26 is a colter secured to the plow-beam by means of the bolts 27.

28 is a disk the journal 29 of which is journaled in the bearing 24. This disk 28 is set 75 at an angle of about forty degrees toward the unplowed land, so that it will tear up and turn the ground, while the top of the disk leans backward about twenty degrees, thus causing the disk to draw into or under the 80 ground when in operation. This disk 28 is adjustable through the medium of the plate 23 upon the standard 2. In this connection it may be stated that when the adjustment of the disk 28 is changed the landside 6 is adjusted accordingly in order that these two elements may coöperate.

85 30 is a bracket or clamp secured to the beam 1 and provided with a set-screw 31.

32 is a scraper provided with a hanging bar 90 33, the upper end of which is secured within the clamp 30 by means of the set-screw 31. This scraper 32 is adapted to free the disk 28 of dirt, &c.

In plowing land with tall or tough grass 95 with a disk plow it has heretofore been found that the disk in many cases merely crushes or presses the grass down into the ground, especially when the ground is very soft. This objection is overcome in my plow by means 100.

of the colter 26, which divides the grass in a straight line immediately in front of the disk 28.

Having thus described my invention, the following is what I claim as new therein and desire to secure by Letters Patent:

1. In a plow of the character described, the combination with a beam, an integral vertically-dependend standard having a series of bolt-openings, a journal-bearing vertically adjustable, secured to said standard, a cutting-disk journaled in said bearing, of a landside, two series of bolt-openings in the same, and a brace provided with a series of bolt-holes in one end, and a single hole in the other, said brace extending from the forward part of the landside to the standard and said landside being adjustable on the standard.

2. In a plow of the character described, the combination with the plow-beam having a depending standard, of a landside having two series of bolt-openings, and a brace, one end of which is provided with a series of bolt-openings; the forward end of said brace being secured in the desired hole of one of the series of bolt-openings in the landside, while

the other end is secured to the standard; said landside being connected to the standard by bolts passing through the other series of bolt-openings.

3. In a plow of the character described, the combination with the plow-beam having a depending straight vertical standard provided with a series of bolt-openings, a plate having a journal-bearing adjustably secured to said standard, a cutting-disk mounted in said journal-bearing at an angle to the standard, and a scraper for said disk; of a landside adjustably secured to the bottom of the said standard, a lug extending from one side of the point of said landside, provided with an upwardly-extending flange, a reversible and adjustable point secured on said lug, an adjustable brace extending from the forward end of the landside and connected to the standard of the beam, and a colter connected to said beam immediately in front of the said disk.

EDWARD FOWLER.
